(57) **CLAIM**

The ornamental design for a lighting fixture, as shown and described.

DESCRIPTION

This application is related to commonly assigned, co-filed U.S. design patent application Ser. No. 29/791,055, filed on Dec. 28, 2021 by Molly E. McGee, entitled "Refractor", commonly assigned, co-filed U.S. design patent application Ser. No. 29/791,056, filed on Dec. 28, 2021 by Molly E. McGee, entitled "Lighting Fixture", and commonly assigned, co-filed U.S. design patent application Ser. No. 29/791,053, filed on Dec. 28, 2021 by Molly E. McGee, entitled "Lighting Fixture", which applications are incorporated herein by reference in their entireties.

FIG. 1 is a front right perspective view from below of a lighting fixture according to the new design;

FIG. 2 is a front left perspective view from above thereof;

FIG. 3 is a front elevational view thereof;

FIG. 4 is a left side elevational view thereof;

FIG. 5 is a right side elevational view thereof;

FIG. 6 is a rear elevational view thereof;

FIG. 7 is a top view thereof; and,

FIG. 8 is a bottom view thereof.

The broken lines in the drawings illustrate portions of the lighting fixture and form no part of the claimed design.

1 Claim, 8 Drawing Sheets
